UNITED STATES PATENT OFFICE.

WILLIAM C. POPE, OF PHILADELPHIA, PENNSYLVANIA.

TRANSFER-TICKET.

No. 796,979.

Specification of Letters Patent.

Patented Aug. 8, 1905.

Application filed February 23, 1905. Serial No. 247,014.

To all whom it may concern:

Be it known that I, WILLIAM C. POPE, a citizen of the United States, residing at Philadelphia, in the county of Philadelphia and State of Pennsylvania, have invented new and useful Improvements in Transfer-Tickets, of which the following is a specification.

This invention relates to certain new and useful improvements in transfer-tickets, more particularly what are termed "time-limit" transfer-tickets generally employed by street-railroads, traction-companies, &c., for transferring from a car of one railway or branch line to a car of another railway or branch line at a given transfer-point; and the object thereof is to enable the conductor or company's agent to issue the transfer to the passenger with as little trouble and in as short a time as is possible at the period of transfer.

Primarily the object of the invention is to provide a transfer-ticket with means hereinafter specifically referred to for indicating simultaneously when issuing the transfer a time limit for the fraction of an hour and whether said fraction of the hour is antemeridian or postmeridian, as the case requires.

With the foregoing and other objects in view the invention consists of the novel form of time-limit transfer-ticket hereinafter more specifically described, and illustrated in the accompanying drawings, which form a part of this specification, and particularly pointed out in the claims hereunto appended.

In describing the invention in detail reference is had to the accompanying drawings, in which—

Figure 1 is a front elevation of a transfer-ticket in accordance with this invention, and Fig. 2 is a like view of a modification.

A transfer-ticket in accordance with this invention comprises a body portion and a plurality of severable coupons provided with conventional indications for indicating the fractions of the hour within which the ticket after being issued is valid for passage.

Referring to Fig. 1 of the drawings, 1 denotes the body portion of the ticket, having at one end a plurality of severable coupons divided into two series, one termed an "antemeridian fraction-of-the-hour time-limit-indicating series," and the other a "postmeridian fraction-of-the-hour time-limit-indicating series." The antemeridian time-limit-indicating series of coupons has conventional means for distinguishing it from the postmeridian time-limit-indicating series of coupons—for

example, one series of coupons being of a different color from the other series. One series of coupons is separated from the other by a postmeridian even-hour-indicating coupon. The antemeridian fraction-of-the-hour time-limit-indicating series of coupons comprises three in number and are indicated by the reference characters 2, 3, and 4, the postmeridian even-hour-indicating coupon by the reference character 4^a, and the postmeridian fraction-of-the-hour time-limit-indicating series of coupons also comprises three in number, and are indicated by the reference characters 5, 6, and 7. The number of coupons of each series may be increased or diminished according to the time limit set for the use of the transfer-ticket. The time limit shown and to be hereinafter referred to is illustrated, by way of example, as well as the number of coupons in each series. The body portion 1 has a column of numerals—for example, "1" to "12"—for indicating the even hours and which are designated by the reference character 8. This column of numerals may be arranged at any suitable point on the body portion; but, as shown, it is at that end opposite to the end to which the coupons are attached. The body portion 1 has also a line of abbreviations, as at 9, for indicating the months of the year and at each side of said line of abbreviations a line of numerals, as at 10, for indicating the days of the month, and the said body portion is further provided with a column of inscriptions to indicate the transfer-points, as at 11; with an inscription, as at 12, to indicate the name of the railroad issuing the transfer-ticket; with an inscription, as at 13, for instructions to the passenger; with the conductor's number, as at 14, and with the transfer-number, as at 15. The coupon 2 is separated from one end of the body portion by a weakened line, as at 16, and has the following legends thereon: "A. M. 15 after hour punched," and which indicates to the passenger that when the transfer is issued and said coupon 2 is attached to the body portion that the transfer-ticket is valid for passage until fifteen minutes after the hour antemeridian. The coupon 3 is separated from the coupon 2 by a weakened line, as at 17, and has the same legend thereon as the coupon 2, with the exception that "30" is used instead of "15," which indicates that if the ticket is issued with the coupon 3 attached the ticket is valid for passage until thirty minutes past the hour antemeridian. The

coupon 4 is separated from the coupon 3 by a weakened line, as at 18, and has the same legends thereon as the coupons 2 and 3, with this exception, that in lieu of either "15" or "30" "45" is upon the coupon 4, which indicates when the transfer-ticket is issued that it is valid for passage until forty-five minutes past the hour antemeridian. Interposed between the coupon 4 and the coupon 5 is the postmeridian even-hour-indicating coupon 4^a, which is a different color from the coupon 4, so as to distinguish it therefrom, as well as from the coupons 2 and 3. The coupon 4^a is separated from the coupon 4 by a weakened line 4^b and has the following legends thereon: "Hour punched is even P. M. hour" and which indicates that when the ticket is issued with the coupon 4^a attached it will be valid for passage postmeridian until the hour punched. The coupon 5, which is a different color from either the coupon 2, 3, or 4, is separated from the coupon 4^a by a weakened line, as at 19, and has the following legends thereon: "P. M. 15 after hour punched" and which indicates that if the ticket is issued with the coupon 5 attached it will be valid for passage until fifteen minutes past the hour postmeridian. The coupon 6, which has the same color as the coupon 5, is separated from the coupon 5 by a weakened line, as at 20, and has the same legends thereon as the coupon 5, with this exception, that "30" is used instead of "15" and which indicates that if the ticket is issued with the coupon 6 attached the ticket is valid for passage until thirty minutes past the hour postmeridian. The coupon 7 is of the same color as the coupon 6 and is separated therefrom by a weakened line, as at 21, and has the same legends thereon as the coupons 5 and 6; but in lieu of "30" or "15" "45" is used instead and which indicates that if the ticket is issued with the coupon 7 attached the ticket will be valid for passage until forty-five minutes past the hour postmeridian. The coupon 7 is separated from a binding-stub 22 by a weakened line 23. It may be well to state at this point that the coupons are issued in tablet form and consecutively numbered, the number being upon the body portion, as heretofore referred to. In lieu of separating each of the coupons from one another and the coupon 7 from the stub 22 and the coupon 2 from the body portion 1 by a weakened line, as shown, they can be separated by a printed divisional line, and a metal plate can be employed with a sharpened edge to facilitate the severing of the ticket at the necessary points, the antemeridian series of time-limit-indicating coupons, the postmeridian even-hour-indicating coupon, and the postmeridian time-limit-indicating coupons associating with the column of numerals indicated by the reference character 8, so that if the conductor punches one of the said numerals of said column of

numerals said punched number associates with that coupon attached with the body portion at the point farthest away therefrom. The column of numerals 8 is also used for indicating that the ticket is valid for passage antemeridian up to the hour punched. For example, if all the coupons were severed from the body portion 1 and one of the numerals of the column of numerals 8 was punched it would indicate that the ticket is valid for passage up to the hour antemeridian indicated by the numeral punched. The body portion 1 is further provided with an enlarged numeral, as at 24, for indicating also the day on which the transfer-ticket is issued.

When using the transfer-ticket, the general points necessary to be punched are punched in advance of the issuance of the transfer-ticket, so that all that is necessary for the conductor to do when issuing the ticket is to punch one of the numbers of the column of numerals 8 and to sever the ticket at the necessary point. If it be severed, for example, at the line 17 and issued, it would indicate that the fraction of the hour is antemeridian; but if severed at the point 20 it would indicate that the fraction of the hour is postmeridian. Therefore when issuing the transfer-ticket two things are accomplished, one of which is the forming of the necessary time limit for which the transfer-ticket is valid for passage and the other of which is whether said time limit is an antemeridian or a postmeridian one.

In the modified construction shown in Fig. 2 but one series of severable coupons is employed, and the said coupons not only associate with the column of numerals for indicating the even hour, but also associate with the column of transfer-points, which is provided in such a manner that when punched will designate the coupons postmeridian or antemeridian, as the case may be. The reference character 25 denotes the body portion, and 26, 27, and 28 denote the severable coupons, which are attached to the body portion and with each other. The body portion 25 is provided with a line of numerals, as at 29, for example, "1" to "12" for indicating the even hours, and the function of said line of numerals is the same as that in connection with the line of numerals 8—that is to say, they associate with the coupons for forming a time limit. The body portion 25 is also provided with a column of inscriptions, as at 30, for indicating the transfer-points. Each inscription is divided into two colors, so that said column of inscriptions will have half thereof in one color and the other half in another color, one of these colors when punched indicating antemeridian and the other of these colors when punched indicating postmeridian. Otherwise than that, as stated, the body portion 25 is the same as the body portion 1, the same reference characters being applied thereto. The coupon 26 has the following legends

thereon: "15 after hour punched." The coupon 27 has the legends "30 after hour punched," and the coupon 28 has the legends "45 after hour punched." The coupons 26, 27, and 28 are separated from one another and from the body portion in a manner referred to in connection with the transfer-ticket shown in Fig. 1, and the legends on the said coupons 26, 27, and 28 are for the same purpose as the legends upon the coupons shown in Fig. 1. The coupons of Fig. 2 become antemeridian or postmeridian time-limit-indicating coupons, according to the way in which the column of inscriptions 30 is punched. If one color of said column be punched, then the coupons become antemeridian time-limit indicating, and if the other color be punched then the coupons become postmeridian time-limit-indicating coupons. Of course it will be assumed that the column of numerals 29 is also punched to associate with the coupon, which is attached with the body portion, but farthest away therefrom. If all the coupons are severed from the body portion, the time limit is the same as that set forth in connection with Fig. 1.

Having thus fully described my invention, what I claim as new, and desire to secure by Letters Patent, is—

1. A transfer-ticket comprising a body portion and a plurality of coupons, each of said coupons having an inscription thereon to indicate the fraction of a single hour and constituting a part of an hour time limit, and said body portion having a series of hour indications, any one of which associating with any one of the inscriptions of the coupons constitutes a complete hour time limit.

2. A transfer-ticket comprising a body portion and a plurality of coupons at one end thereof, each of said coupons having an inscription thereon to indicate the fraction of a single hour and constituting a part of an hour time limit, and said body portion having a series of hour indications, any one of which associating with any one of the inscriptions of the coupons constitutes a complete hour time limit.

3. A transfer-ticket comprising a body portion and a plurality of coupons extending transversely with respect to the body portion and arranged in parallelism with respect to each other, each of said coupons having an inscription thereon to indicate the fraction of a single hour and constituting a part of an hour time limit, and said body portion having a series of hour indications, any one of which associating with any one of the inscriptions of the coupons constitutes a complete hour time limit.

4. A transfer-ticket comprising a body portion and a plurality of independent coupons, each of said coupons having an inscription thereon to indicate one fraction of an hour and constituting a part of an hour time limit,

the inscriptions of each of the coupons indicating a different fraction of the hour, and said body portion having a series of hour indications, any one of which associating with any one of the inscriptions of the coupons constitutes a complete hour time limit.

5. A transfer-ticket comprising a body portion and a plurality of independent coupons at one end thereof, each of said coupons having an inscription thereon to indicate one fraction of an hour and constituting a part of an hour time limit, the inscriptions of each of the coupons indicating a different fraction of the hour, and said body portion having a series of hour indications, any one of which associating with any one of the inscriptions of the coupons constitutes a complete hour time limit.

6. A transfer-ticket comprising a body portion and a plurality of independent coupons at one end thereof extending transversely with respect thereto and arranged in parallelism with respect to each other, each of said coupons having an inscription thereon to indicate one fraction of an hour and constituting a part of an hour time limit, the inscriptions of each of the coupons indicating a different fraction of the hour, and said body portion having a series of hour indications, any one of which associating with any one of the inscriptions of the coupons constitutes a complete hour time limit.

7. A transfer-ticket comprising a body portion and two series of coupons, one of said series having a conventional indication for distinguishing it from the other of said series, each coupon of each series having a conventional indication to constitute a part of a time limit, and said body portion having a conventional indication associating with any one of the indications of one series of coupons for constituting a complete antemeridian time limit and associating with any one of the indications of the other series of coupons for constituting a complete postmeridian time limit.

8. A transfer-ticket comprising a body portion and two series of coupons at one end thereof, one of said series having a conventional indication for distinguishing it from the other of said series, each coupon of each series having a conventional indication to constitute a part of a time limit, and said body portion having a conventional indication associating with any one of the indications of one series of coupons for constituting a complete antemeridian time limit and associating with any one of the indications of the other series of coupons for constituting a complete postmeridian time limit.

9. A transfer-ticket comprising a body portion and two series of coupons at one end thereof and extending transversely with respect thereto and arranged in parallelism with respect to each other, one of said series having

a conventional indication for distinguishing it from the other of said series, each coupon of each series having a conventional indication to constitute a part of a time limit, and said body portion having a conventional indication associating with any one of the indications of one series of coupons for constituting a complete time limit.

10. A transfer - ticket comprising a body portion and two series of coupons, one of said series having a conventional indication for distinguishing it from the other of said series, each coupon of each series having a conventional indication to constitute a part of a time limit, the indications of the coupons of their respective series varying with respect to one another, and said body portion having a conventional indication associating with any one of the varying indications of one series coupons for constituting a complete antemeridian time limit, and associating with any one of the varying indications of the other series of coupons for constituting a complete postmeridian time limit.

11. A transfer - ticket comprising a body portion and two series of coupons at one end thereof, one of said series having a conventional indication for distinguishing it from the other of said series, each coupon of each series having a conventional indication to constitute a part of a time limit, the indications of the coupons of their respective series varying with respect to one another, and said body portion having a conventional indication associating with any one of the varying indications of one series of coupons for constituting a complete antemeridian time limit, and associating with any one of the varying indications of the other series of coupons for constituting a complete postmeridian time limit.

12. A transfer - ticket comprising a body portion and two series of coupons at one end thereof and extending transversely with respect thereto and arranged in parallelism with respect to each other, one of said series having a conventional indication for distinguishing it from the other of said series, each coupon of each series having a conventional indication to constitute a part of a time limit, the indications of the coupons of their respective series varying with respect to one another, and said body portion having a conventional indication associating with any one of the varying indications of one series of coupons for constituting a complete antemeridian time limit, and associating with any of the varying indications of the other series of coupons for constituting a complete postmeridian time limit.

13. A transfer - ticket comprising a body portion, two series of coupons and a coupon interposed between the two series of coupons, said single coupon and one of said series of coupons having a conventional indication for

distinguishing them from the other of said series of coupons, each coupon of each series and said single coupon having a conventional indication to constitute a part of a time limit and said body portion having a conventional indication associating with any one of the indications of one series of coupons for constituting a complete antemeridian time limit and associating with any one of the indications of the other series of coupons and said interposed coupon for constituting a complete postmeridian time limit.

14. A transfer - ticket comprising a body portion, two series of coupons and a coupon interposed between the two series of coupons, said coupons at one end of said body portion, said single coupon and one of said series of coupons having a conventional indication for distinguishing them from the other of said series of coupons, each coupon of each series and said single coupon having a conventional indication to constitute a part of a time limit and said body portion having a conventional indication associating with any one of the indications of one series of coupons for constituting a complete antemeridian time limit and associating with any one of the indications of the other series of coupons and said interposed coupon for constituting a complete postmeridian time limit.

15. A transfer - ticket comprising a body portion and a plurality of coupons, each of said coupons having an inscription thereon to indicate the fraction of a single hour and constituting a part of an hour time limit, and said body portion having a series of hour indications, any one of which associating with any one of the inscriptions of the coupons constitutes a complete hour time limit and said hour indications being so designated that each constitutes in itself a complete hour time limit.

16. A transfer - ticket comprising a body portion and a plurality of coupons at one end thereof, each of said coupons having an inscription thereon to indicate the fraction of a single hour and constituting a part of an hour time limit, and said body portion having a series of hour indications, any one of which associating with any one of the inscriptions of the coupons constitutes a complete hour time limit and said hour indications being so designated that each constitutes in itself a complete hour time limit.

17. A transfer - ticket comprising a body portion and a plurality of coupons extending transversely with respect to the body portion and arranged in parallelism with respect to each other, each of said coupons having an inscription thereon to indicate the fraction of a single hour and constituting a part of an hour limit, and said body portion having a series of hour indications, any one of which associating with any one of the inscriptions of the coupons constitutes a complete hour time limit

and said hour indications being so designated that each constitutes in itself a complete hour time limit.

18. A transfer-ticket comprising a body portion and a plurality of independent coupons, each of said coupons having an inscription thereon to indicate one fraction of an hour and constituting a part of an hour time limit, the inscriptions of each of the coupons indicating a different fraction of the hour, and said body portion having a series of hour indications, any one of which associating with any one of the inscriptions of the coupons constitutes a complete hour time limit and said hour indications being so designated that each constitutes in itself a complete hour time limit.

19. A transfer-ticket comprising a body portion and a plurality of independent coupons at one end thereof, each of said coupons having an inscription thereon to indicate one fraction of an hour and constituting a part of an hour time limit, the inscriptions of each of the coupons indicating a different fraction of the hour, and said body portion having a series of hour indications, any one of which associating with any one of the inscriptions of the coupons constitutes a complete hour time limit.

limit and said hour indications being so designated that each constitutes in itself a complete hour time limit.

20. A transfer-ticket comprising a body portion and a plurality of independent coupons at one end thereof extending transversely with respect thereto and arranged in parallelism with respect to each other, each of said coupons having an inscription thereon to indicate one fraction of an hour and constituting a part of an hour time limit, the inscriptions of each of the coupons indicating a different fraction of the hour, and said body portion having a series of hour indications, any one of which associating with any one of the inscriptions of the coupons constitutes a complete hour time limit, and said hour indications being so designated that each constitutes in itself a complete hour time limit.

In testimony whereof I have hereunto set my hand in presence of two subscribing witnesses.
